UNITED STATES PATENT OFFICE.

JOHN BYRON GOLDSBOROUGH, OF CROTON NEW YORK, ASSIGNOR TO THE UNDER-PINNING COMPANY, OF NEW YORK N. Y., A CORPORATION OF NEW YORK.

METHOD AND APPARATUS FOR CONSTRUCTION OF SUPPORTS OF BUILDINGS AND OTHER STRUCTURES.

961,438.

Specification of Letters Patent. Patented June 14, 1910.

Application filed March 19, 1909. Serial No. 484,499.

To all whom it may concern:

Be it known that I, JOHN BYRON GOLDSBOROUGH, a citizen of the United States, residing at Croton, in the county of Westchester and State of New York, have invented certain new and useful Improvements in Methods and Apparatus for Construction of Supports of Buildings and other Structures, of which the following is 10 a full, clear, and exact specification.

This invention relates generally to the construction of supports for buildings, building walls, and other structures, particularly to that type of such supports 15 wherein hollow foundation elements are employed to support such structures, and it will be found to be available in connection with the method of sinking such foundation elements set out in the Breuchaud Patent 20 No. 563,130, dated June 30, 1896. It may also be employed in connection with hollow foundation elements, whether sunk by the Breuchaud method or not. It may also be employed in connection with such hollow 25 foundation elements, whether sunk under an existing wall to support the same, or sunk preliminary to the erection of any structure as a foundation for a new structure. My invention is therefore equally available for 30 use in connection with a new support or foundation for an already-erected structure, or for use in connection with a support or foundation upon which a new structure is to be erected.

35 The invention has for its object to provide a method and apparatus whereby the footing and consequently the supporting power of such hollow foundation elements may be increased, whether the same be deep or shallow, and thereby to enable a smaller foundation element to be sunk, which will take less time and cause less friction and expense than if a large foundation element were sunk, and to give it the bearing or supporting power of such larger element; further, 40 that I am enabled to obtain all the advantages of a deep foundation without the loss of time and expense usually incident to such foundation.

45 A further object is to enable the bearing or supporting power of foundation elements to be made substantially uniform, whether they are of the same or different diameters in cross-section, and whether they are sunk

to the same depth or to different depths, and 55 whether they are equally or unequally loaded, and thereby I accomplish the important advantage that the resistance of the foundation to settlement, etc., is equalized, and in case of a settlement of the foundation, all 60 parts thereof will settle equally and liability to injury thereby be avoided; whereas, were the resistance of the foundation to settling unequal, the walls would be cracked and possibly the structure demolished. 65

A further object of my invention is that it enables me to connect the bases or footings of adjacent hollow foundation elements by additional and increased footings, whereby they not only have their bearing power 70 largely increased, but have increased interdependence, solidity, and rigidity, and any tendency to tilting or sidewise motion for any cause is overcome.

A further object of my invention is that 75 it enables me to provide a sufficient foundation for a building, no matter how heavy, without the necessity of going to bed-rock or hard-pan.

A further object of my invention is that 80 it enables me to increase at will the supporting power of a foundation to any desired limit within its intrinsic resistance.

By the term "hollow foundation element," I intend to include all such hollow foundations as may be located in the earth, whether round or square, or of other shape in cross-section, and whether the said foundation element, in itself, is the sole support, or whether it is strengthened by a filling of 90 concrete, cement, brick, etc., and whether such element be styled cylinders, columns, caissons, or other name be applied thereto, and whether the same be sectional or integral. 95

These, and other objects which will appear as the description proceeds, I attain by the method hereinafter described, and by the use of the apparatus illustrated in the accompanying drawings— 100

Figure 1 is a vertical section through the lowermost part or footing of a supporting foundation element, the upper part being broken away, illustrating the employment of two varieties of extended footings; also 105 the method employed of adjusting one of said footings to position. Fig. 2 is a similar view illustrating the method of adjusting

the other of the extended footings illustrated in Fig. 1 to place. Fig. 3 is a similar view illustrating the employment of a modified form of footing, as well as the 5 method by which the same is driven to place. Fig. 4 is a diagrammatic plan illustrating in its perpendicular wings the extended footings of Fig. 1, and in its horizontal wings the upper extended footings of 10 Fig. 1 and the lower or modified form of footings of Fig. 3, illustrating, also, the manner of connecting these latter footings. Fig. 5 is a detail, partly in section, of the 15 manner of connecting the modified form of footings of Fig. 3. Fig. 6 is a view, similar to Fig. 1, illustrating the upper extended footings of that figure, with a brace which may be employed, and illustrating, also, the employment of grouting pipes. Fig. 7 is a 20 vertical section of the lower ends and footings of several adjacent foundation elements, illustrating, also, the extended footing in place beneath the footing of adjacent foundation elements connecting the same. 25 Fig. 8 is a diagrammatic plan of the construction of Fig. 7, illustrating the employment of different varieties of extended footings; and Fig. 9 is a detail in cross-section of one form of extended footing, showing 30 adjacent members connected.

My extended footings are best applied in connection with hollow foundation element 1, which may be in the form either of a cylindrical column or caisson, or in the form 35 of a rectangular column or caisson. The particular form of foundation element is not important to my present invention, save in so far as that it is most convenient to apply my extended footings in connection with a 40 hollow column or caisson. Nor is my present invention limited by the manner of constructing said foundation-element, etc. The same may be sunk sectionally by the resistance furnished by the weight of the already- 45 erected wall, as in the said Breuchaud patent, or they may be sunk in the usual manner of constructing foundation caissons by the use of added weights. The pneumatic process may be employed where advisable 50 in sinking such foundation elements, or a water jet may be used.

Where my method and apparatus are employed in connection with the Breuchaud patented method, they make a valuable adjunct to that method, for they permit a foundation element to be sunk of the smallest cross-sectional area requisite to support the compression load, and I increase the 55 footing to any extent necessary to furnish a safe support for such foundation, without carrying the same down to bed-rock. For instance, we will assume that the load to be borne by such foundation element would be one hundred tons. Assuming that this foundation 60 were to be driven to bed-rock, it need

only have sufficient material in cross-section to support the load. As bed-rock is frequently met with only at a great depth, it is very expensive and tedious to be compelled to drive the foundation so far. If, however, 70 the foundation elements stop short of bed-rock, for instance, in sand, they must then have a footing which is increased in area as the sand is diminished in bearing power; e. g., in the case supposed, if sand were allowed to carry a load of four tons to the square foot, a foundation of twenty-five square feet would be required. It would probably be impossible to sink a foundation of this size, by the resistance of the wall, to a safe depth. But by my invention the foundation need be no larger than required to furnish the needed strength, and the footing can be extended as required, and therefore a much smaller foundation may be employed, and it may safely be stopped at a point above the bed-rock where the same is at a great depth. It may be found advantageous to excavate somewhat below the bottom of the foundation before beginning the work of inserting my invention in cases where it is used at the base thereof, although this is not essential, as the extended footings may be used in cases where such excavation is not feasible; for instance, in wet soil, 85 as quicksand, which nevertheless has considerable supporting power when confined so that it may not flow freely.

Broadly, my invention consists in the employment of extended and extensible footings which are inserted and fixed in place after the supporting foundation is sunk, and which may be placed either at the lower extremity thereof or at an intermediate point. Care, however, should be taken to locate the 100 said extended footings at a point below where the earth is liable to be much disturbed by future constructions. In Figs. 1, 2, and 3 I have illustrated a convenient form which such extended footing may take, and here it is illustrated as an elbow-bracket 2, having vertical-flange 3, horizontal-flange or footing 4, and connecting web or brace 5, which passes through slots 2^A in the caisson 1. In Fig. 4 I have illustrated such brackets 2, as extending substantially the width of one side of a rectangular caisson, and as provided with two webs or braces 5 each. Obviously this is a matter of detail which may be varied without departing from the 105 invention, and more or less sections be used to a side, and more or less braces employed. The tendency of the elbow-brackets 2, when the column 1 is bearing its load, will be for the outer end of the footing 4 to tip up, causing the upper ends of vertical-flanges 3 to approach each other. In case the foundation element is filled with concrete, as is usually the case, not only for the added 110 strength, but as a preservative, this concrete 115

filling will resist the tendency of the flanges 3, and will cause the brackets 2 to be stiff and rigid; but in cases where the concrete filling is not employed, other means are made use of to stiffen the said brackets. For instance, in Figs. 4 and 5 I have illustrated a brace-bar 6, bolted to brackets 7, on the vertical flanges 3, of the right and left hand elbow-brackets 2. As seen in Fig. 4, the upper and lower brackets 2, being first inserted, are made the full width of the foundation element 1, and their vertical-flanges 3 lie behind and are supported by the edges of the right and left hand brackets 2, which are of less width and lie between the vertical flanges of the upper and lower brackets.

When the foundation element 1, which may represent the working chamber of a caisson sunk by the pneumatic process, has been sunk or driven to its proper place, and the load which the same will bear has been ascertained, and the extent to which its footing must be enlarged to harmonize with the other foundation elements, sections of extended footings 2, having the proper area of bearing-surface 4, will be lowered into the working chamber, and having been inserted in place with the web or brace 5 in position to enter slot 2^A, a screw or hydraulic-jack 8 (Fig. 1), will be placed with one end bearing against the inner end of the horizontal-flange or foot 4, and the other end against the walls of the foundation 1, or the opposite bracket 2, and the jack being operated, the section of extended footing will be driven to place. Of course, should it not be necessary to extend the footing of the foundation to such an extent as to require four of the sections 2, only two of such sections need be employed. It is advisable to employ an even number and to situate them opposite each other to avoid an eccentric loading on the base. In case the foundation is eccentrically loaded, the extended footings should be so located with relation to the load or center of gravity as evenly to distribute the load thereon. In certain cases, as where a foundation is on the border of a lot, an eccentric loading of same and the extended footings may be necessary, and where it may not be possible to locate them opposite each other. By increasing or diminishing the extent to which the flange or foot 4 projects, or by decreasing the width of such flange, almost any desired extent of bearing surface may be obtained. Means are also provided whereby an auxiliary extended footing may be introduced, and this will be found valuable in many cases, for it not only extends the footing or bearing surface of the foundation to a considerable extent, but it provides means by which the footings of adjacent foundation elements may be connected, and a continuous footing introduced from beneath one foundation element to an-

other adjacent one, and the whole connected so as to furnish practically a continuous, united grillage or net-work of beams uniting all of said elements. In Fig. 1 this auxiliary extended footing is represented as a shoe 10, 70 comprising a horizontal-plate 11, provided with stiffening-ribs or braces 12. Three of such ribs are illustrated on the under side of each plate in Fig. 1, but a greater or less number may be used, and the shoe 10 may be 75 of the width of the foundation element, as illustrated in Fig. 1, or of less width. The shoe is inserted in place by a screw or other jack 13, which engages in the bight of a stirrup 14, the hooks of which pass over the 80 inner end of the shoe 10. The opposite end of the jack engages against the opposite side of the foundation element 1, or below bracket 2. The operation of the jack causes the shoe to pass out under elbow-bracket 2, 85 to the position illustrated in Fig. 1, and it is anchored in position by the anchor or tie-piece 15, having a bent end 16, which passes over the upper end of vertical-flange 3, and a similarly bent-end 17, which passes under 90 plate 11. The auxiliary extended footing may be made in the form of a pipe 18, as illustrated in Fig. 3, and for many purposes possibly this will be the preferred form. It is easily inserted in place by the use of a 95 stirrup 14 and jack 13, as illustrated in Fig. 3, the manner of insertion being the same as that of the shoe 10. The pipes 18 are preferably perforated as illustrated (Fig. 100 3) for the purpose of grouting, the advantages of which are that a large body like solid rock is formed about the footing, increasing its bearing power and preserving the metal employed from rust. Where the pipes 18 are employed, they may be connected and made rigid by the means illustrated in detail in Fig. 5 and in plan in Fig. 4. Here short cylindrical plugs 19 are employed, one being inserted in the end of each of the opposite pipes 18, and these 110 plugs are joined by a sliding sleeve 20, which fits over their adjacent free ends, or a screw coupling may be employed if desired.

In Fig. 4 I have illustrated the employment of shoes 10, in the upper and lower auxiliary extended footings, and on the right and lefthand sides the employment of pipes 18, with couplings 19, 20. Where my extended footing passes beneath the walls of 115 adjacent foundation elements, it may not be necessary to brace the ends within the hollow foundation elements by the employment of additional braces, owing to the fact that weight is upon each end of said extended 120 footings and they are thereby braced by the foundation elements. Should it be desired to employ the pipes 18 on all four sides of the foundation element and to connect them 125 all where they pass under the same, one set 130

may pass under the other, and filling blocks 21 interposed between the lower edge of the foundation element and the upper surface of the pipes 18 (Fig. 8). In cases where the auxiliary extended footing is not required, the bracket 2 may alone be employed to extend the footing, and in such cases the said bracket should preferably be inverted in position, thereby enabling it to be placed below the foundation element and dispensing with the necessity for slots therein to receive the web 5, as the said web would then be located below the side walls of the foundation element 1. In such case the earth at the bottom of the foundation element would be excavated sufficiently to enable the bracket to be inserted and when the brackets were in place the cavity could be filled with concrete, thereby bracing the brackets, or other braces could be employed.

In Figs. 7 and 8 I have illustrated a group of foundation elements designed to serve as a foundation for a new structure, and wherein their bases or footings are connected by a series of extended footings so as to make the whole a rigid, substantially homogeneous structure, and wherein all the foundation elements are so supported that the maximum footing or bearing surface is obtained and likewise movement is prevented. It will be noted that by the construction illustrated in these two figures, any desired number of foundation elements may be put down to any desired depth, and extended footings forced out therefrom so as to form a solid subterranean beam or grillage extending under or through the base portion of the foundation in such a way as to affect all the foundation elements supporting a building or other structure at any depth below the surface to which it may be desired to transfer the weight of the building or structure.

In Fig. 7 I have illustrated a sectional extended footing 22, which is composed of short lengths or sections of channel iron which may be inserted in place in the manner illustrated in Fig. 3, and where the rigidity is obtained by side-strips or stays 23, bolted thereto before being forced to place. This will serve as a fastening where the channel irons are separated, as seen in the right and lefthand wings or extended footings of Fig. 8, and where they are employed adjacent to each other their inner flanges may be bolted together, as at 24 in Fig. 9, in which case the channel iron is arranged so as to break joints, as in the upper wings of Fig. 8.

In the plan view of Fig. 8, I have illustrated the employment of both varieties of extended footings; viz., pipes 18 and channel irons 22, not intending to indicate thereby that they must or should be used together, but to save space. Where I have illustrated channel irons, other commercial forms such

as T irons, having flanges adapted for bolting, might in some cases be used.

Where several sections of pipe are employed to construct an extended footing between the footings of adjacent foundation elements, as in Fig. 8, means must be provided to stiffen the same and to give the several sections the stiffness of an integral structure, which may consist of sectional plugs 25, arranged so as to break joints with the pipes.

The different ways I have illustrated of connecting the extended footings together so as to make them rigid are illustrative merely, and my invention does not reside in the particular manner of making such connections, as many ways of making them will be available to the engineer. Furthermore, should it be deemed advisable to connect the bases of the foundation elements to prevent side-wise movement, this may be done by suitable means—for instance, by angle irons 26 (Fig. 8), secured to the upper surfaces of the channel irons 22 and to the body of the foundation elements 1.

I have shown in various places the use of appliances which permit the employment of grout, and in Fig. 6 I have shown pipes 46, designed particularly to facilitate the introduction of grout into and around the extended footings 2. In all cases it may not be necessary to employ such pipes, as in many instances the provision of a hole in the wall of the hollow foundation element is sufficient.

The great advantage of this type of construction is that small foundation elements may be used for the support of heavy buildings which will safely transfer the weight of the building to a greater depth which will be entirely below any possible future disturbance caused by the building of subways, tunnels, or deep open excavations in the vicinity of the building or other structure, the foundation of which has been constructed by the method described. By this means buildings of any weight may be cheaply and safely supported on what would otherwise be unstable material, or where the character of the soil is such that the cost of securing a foundation by the present methods of open excavation or caissons is prohibitive. Desirable building sites are rendered unavailable owing to the high costs by present methods of building foundations to rock or to a considerable depth in or through material of an unstable character, and the method herein described is intended to overcome these obstacles.

An advantage of my invention is that the forcing out of the extended footings tends to compress and consolidate the soil through and into which they are forced, thereby increasing the bearing power of the soil and decreasing its liability to permit settlement.

This invention is equally applicable to the support of tunnels, both subterranean and sub-aqueous, as it is to the support of buildings, and I intend to include such tunnels in the term "other structures" in the claims. It is known that such tunnels, when driven below rivers, frequently through necessity are driven through unstable soil but ill-adapted to support a tunnel structure and maintain it in stable condition, and that such tunnel structures, while they need support to prevent sinking, also frequently need support to prevent their rising.

An important application of my invention is in connection with sub-aqueous tunnels or tunnels constructed through soil which does not afford a proper bearing surface and consists in the lateral projection of such extended footings directly from the tunnel itself into the adjacent soil, either above, below, or at the sides of the tunnel. Such tunnels, as now constructed, have large sectional iron plates with inwardly-projecting flanges and are lined with brickwork or concrete. The extended footings will in such cases project radially from between the longitudinal joints of adjoining sections of the iron casing of the tunnel and have its inner end secured between the flanges of adjacent sections. In such application the longitudinal axis of the extended footing will be parallel with the longitudinal axis of the tunnel, rather than at right angles to the cylinder. Such extended footings may be arranged throughout the entire length of a tunnel if desired.

An important advantage of my invention is the facility it offers to have all foundation elements for one job made of uniform size, and even for different jobs, by reason of the ease with which the same may afterward, by the use of a greater or less number or size of extended footings, be adjusted to different loads. This renders the construction of a large number of such foundation elements more economical, quicker, and more satisfactory in many ways, such as handling, etc.

It will be perceived that, where I have illustrated the employment of pipes to be forced laterally from the footing of a hollow foundation element into the earth, and which will itself, when properly braced, provide the additional support for such foundation element, the pipe which is so forced may be of light material, such as stove pipe having sufficient strength to enable it to be forced into the earth, and that the said pipe may then be filled with concrete, which may be reinforced by metal if desired, and which may extend across the bottom of the foundation element, and which will, when set, furnish the additional or extended footing, or the pipes which in themselves are adapted to provide such extended footing, may be

braced and strengthened by the introduction therein of such reinforced concrete, in which the plugs illustrated may not be required.

The material of which my extended footings will preferably be made will be such as will have the requisite strength and will not deteriorate in the presence of water. For this purpose, concrete, or concrete reinforced with metal, may well be employed, or metal which will not corrode, as brass, etc. If metal is employed, it need not necessarily have in itself the requisite strength, but may be strengthened by concrete, which may be inserted beneath the same.

Where the nature of the soil will permit, my extended footings may be placed and secured in position by excavating, and thereby assist the use of the jack or perhaps entirely dispense with it. This will be in cases where the water and soil do not flow too freely and where they can easily be kept back or controlled by the aid of air pressure.

What I claim and desire to secure by Letters Patent is:

1. The herein-described method of constructing supports for buildings and other structures, which consists in sinking a hollow foundation element, in then projecting extended footings laterally therefrom, and in then bracing said extended footings and fixing them in position relative to the foundation element so as to be held against relative movement when the foundation element is loaded, substantially as described.

2. The herein-described method of constructing supports for buildings and other structures, which consists in sinking a hollow foundation element, in then arranging an extended footing in position to be forced laterally with respect to said foundation element, in then arranging a jack in position to engage said extended footing and to force the same laterally into the earth by resistance of the walls of the said foundation element, and in then bracing the said extended footings in position.

3. A support for a building or other structure, comprising a hollow foundation element, an extended footing therefor composed of separate sections, each section extending from within such foundation element laterally into the earth, and means for fixing the said extended footing in position relative to said foundation element, at or near the base thereof, to hold the said extended footing against vertical displacement.

4. A support for a building or other structure, comprising a plurality of hollow foundation elements, separate, oppositely-disposed, sectional extended footings projecting laterally into the earth from within each foundation element adjusted to equalize the supporting power of each foundation element, and means for permanently securing said extended footings in position relative to

said foundation element at or near the base thereof to hold them against vertical displacement.

5. A support for a building or other structure, comprising a hollow foundation element, an extended footing or bearing-plate projecting laterally into the soil from a point within the vertical plane of the side walls of said foundation element, means for 10 permanently holding said bearing-plate in place, a brace for said bearing-plate, and means for anchoring same at both ends, substantially as described.

6. A support for a building, tunnel, or 15 other structure, comprising a hollow foundation element, separate, oppositely-located, extended footings projecting laterally from points within the vertical planes of the walls of the hollow foundation element into the 20 soil, and connections permanently securing each of said extended footings to said foundation elements at or near the base thereof.

7. A support for a hollow structure comprising separate extensions projecting laterally from within the same into the adjoining soil or material, and permanently fixed 25 in position with relation to the said structure.

8. The herein-described method of 30 constructing supports for buildings or other structures, which consists in sinking a hollow foundation element having its lower end open, in then arranging an extended footing or support in position to be forced into 35 the earth outside of said foundation element, in then locating a jack in position to engage said extended footing and forcing the same into the earth outside of the vertical planes of the side walls of said foundation element, in then repeating said operation 40 until the footing or supporting surface for said foundation element has been sufficiently extended, and in then bracing and fixing the said extensions in position relative to said foundation element, so as to hold 45 them against movement relative thereto.

9. The herein-described method of 50 constructing supports for buildings and other structures, which consists in locating a hollow structure within the earth, in then projecting extended footings laterally therefrom into the earth, and in then securing the said extended footings in position relative to said foundation element so as to 55 hold the same against relative movement under load.

10. A support for a building or other structure, comprising a hollow foundation element, extended footings projecting laterally from points within the vertical planes 60 of the walls of the foundation element into the soil and braced and fixed against move-

ment relative to said foundation element under load.

11. A support for a building or other 65 structure, comprising a hollow foundation element, extended footings located at the base thereof and projecting laterally from points within the vertical planes of the walls of the foundation element into the soil, and 70 means located at said base for permanently securing the said extended footings against lateral displacement under load.

12. A support for a building or other 75 structure, comprising a hollow foundation element, extended footings located at the base thereof and projecting laterally from points within the vertical planes of the walls of the foundation element into the soil, means for bracing the said extended footings 80 against lateral displacement under load comprising brackets having a horizontal footing located substantially outside said vertical planes, a flange, and means for permanently fixing said bracket in position relative to the foundation element and for holding said bracket against relative movement.

13. A support for a building or other 85 structure, comprising a hollow foundation 90 element, extended footings located at the base thereof and projecting laterally from points within the vertical planes of the walls of the foundation element into the soil, comprising brackets having a plane footing 95 substantially outside said vertical planes, a vertical flange accessible from the interior of said foundation element, a web connecting said footing and flange, and means for holding said bracket against relative displacement.

14. A support for a building or other 100 structure, comprising a hollow foundation element, extended footings located at the base thereof and projecting laterally from 105 points within the vertical planes of the walls of the foundation element into the soil, comprising brackets having a footing substantially outside said vertical planes, a vertical flange accessible from the interior of said 110 foundation element, a web connecting said footing and flange, and a filling of concrete or similar material within the foundation element at the base, engaging said flanges and holding said brackets against displacement.

In testimony whereof, I have hereunto set my hand in the presence of two subscribing witnesses.

JOHN BYRON GOLDSBOROUGH.
